UNITED STATES PATENT OFFICE

2,603,762

ULTRAHIGH-FREQUENCY ELECTRON
DISCHARGE DEVICE

Frank Douglas Goodchild, London, England, assignor to International Standard Electric Corporation, New York, N. Y., a corporation of Delaware

Original application September 9, 1942, Serial No. 457,795. Divided and this application August 10, 1948, Serial No. 43,382. In Great Britain February 14, 1941

4 Claims. (Cl. 315—5)

1

This application is a division of the application Serial No. 457,795, now Patent No. 2,451,328, filed September 9, 1942, by applicant jointly with C. H. Foulkes now converted to a sole application of said C. H. Foulkes; and relates to electron discharge devices and more particularly to such devices of the kind embodying hollow resonators, as for example, electron discharge devices employing velocity modulation of an electron stream.

An object of the invention is the provision of a simple construction of a mount for the electrodes and the resonator for such devices.

According to one aspect of the invention an ultra high-frequency electron discharge device comprises a resonator arranged so that its axis is parallel to the major axis of the bulb and mounted upon a metal platform secured to a plurality of pins fused into a dished glass base onto which the bulb is sealed.

One embodiment of the manner in which the invention is carried out will be described with reference to an electron velocity-modulated device of the kind described in United States Patent No. 2,320,860, dated June 1, 1943, in which the hollow resonator comprises a short length of coaxial line.

In the accompanying drawings:

Figure 1 is a perspective view of the assembled resonator tube and its associated socket;

Figure 2 is a vertical section through the centre of assembly and

Figure 3 is a plan of the base at a section taken on the line 3—3 of Figure 2.

Figures 1 and 2 show how the resonator and its associated electrodes are mounted so that its axis is parallel to the major axis of the enclosing bulb, on a base of the kind comprising a dished glass member 9, the peripheral lip of the member 9 is fused to a lip on the lower end of the enclosing glass bulb 10. Contact pins 11 are sealed directly into the dished member 9. The inner conductor of the resonator is made up of two copper rods 30 and 31, each having one end spread out into a head of mushroom form. The small ends of the rods support an assembly of fins 32 which defines the slot through which the electron stream is fired. The outer conductor 35 is fixed at both ends to the mushroom heads of the rods.

The resonator is mounted upon a triangular copper plate 12 by means of a copper rod 25 screwed into the head of the rod 30, the washer 26 providing the necessary spacing. The plate 12 is spot welded to three of the base pins 11.

2

This permits the resonator to be located near the base and assists in dispersing the heat which is generated. The triangular plate 12 also has cut in it three slots 27 to enable it to take up any strains which may be caused by unequal expansion of the glass and copper. The anode 8, the collector plate 24, the grid 28 and the cathode 29 are mounted upon rods 13 which pass through the mica insulators 14 and 15 and through mica spacing plates 16. The remaining pins 11 in the base are used for connections to the electrodes.

The hole 5, Fig. 2, provides communication between the resonator and the glass tube 17 which is sealed into the bulb 10 adjacent the hole 5. Conductors 18 for extracting energy from the resonator extend through the tube 17 and are sealed thereto at 19.

When the valve is plugged into its socket 20, the three pins 11 which support the triangular platform or plate 12 engage in holes drilled in a substantial metal spider 21 fixed to the socket. The remaining pins engage contact terminals 22 on the socket in the usual manner. The socket 20 is provided with a central hole 33 having a key-way 34 into which the protruding metal spigot containing the sealing off tube of the glass bulb 10 extends. This spigot has a key which engages with the key-way 34 so as to ensure that the pins 11 make contact with the proper terminals 22 of the socket.

The invention is not limited to the precise construction described and modifications coming within the scope of the appended claims will occur to those versed in the art. For example, the outer conductor of the resonator may be built up from three or more curved sections of suitable shape.

What is claimed is:

1. An ultra high frequency electron discharge tube comprising an elongated envelope having a glass base at one end thereof, a plurality of pins fused through said base, a metal platform secured to said pins, a resonator having a center conductor structure mounted upon said metal platform, electrodes disposed adjacent said resonator in said envelope, insulated means carried by said center conductor structure for supporting said electrodes adjacent said resonator, and said platform having slots therein extending inwardly from its edges to enable it to take up any strains which may be caused by unequal expansion of said envelope and of said pins.

2. An ultra high frequency electron discharge tube comprising an elongated envelope having a glass base at one end thereof, a plurality of pins fused through said base, a metal platform having

slots therein extending inwardly from its edges, said platform being secured to said pins, each of said slots being disposed adjacent one of said pins and crosswise of a radial line drawn from the center of said platform through the pin adjacent such slot, a resonator mounted upon said metal platform and having its axis parallel to the major axis of said envelope and electrodes disposed adjacent said resonator in said envelope.

3. An ultra high frequency electron discharge tube comprising an elongated envelope having a glass base at one end thereof, pins fused through said base, a triangular metal platform secured at its corners to three of said pins, said platform having a slot disposed adjacent each of said three pins and extending from the edge of the platform across a line drawn through the center of said platform and the pin adjacent such slot, a resonator mounted upon said metal platform and having its axis parallel to the major axis of said envelope and electrodes disposed adjacent said resonator in said envelope for connection to other of said pins.

4. An ultra high frequency electron discharge tube comprising an elongated envelope having a dished glass base at one end thereof, a plurality of pins fused through said base, a metal platform secured to said pins, a resonator mounted upon said metal platform and having its axis parallel to the major axis of said envelope, insulating discs mounted on said resonator at its respective ends, rods secured at each end in said insulating discs, and electrodes mounted on said rods.
